MEANS FOR POSITIVELY OPENING A VALVE BY PULLING.

1,255,364.

Specification of Letters Patent.

Patented Feb. 5, 1918.

Application filed March 25, 1914. Serial No. 827,076.

To all whom it may concern:

Be it known that I, HENRY WAIBEL, a citizen of the United States, residing at Cleveland, in the county of Cuyahoga and 5 State of Ohio, have invented a new and useful Improvement in Means for Positively Opening a Valve by Pulling, of which the following is a specification, the principle of the invention being herein explained and 10 the best mode in which I have contemplated applying that principle, so as to distinguish it from other inventions.

My invention offers its special utility in connection with the valves of fire-emergency 15 stand pipes or such as are required along the various floors of large buildings.

The general object of the inventive conception has been the provision of a contrivance which will effect the opening of such 20 a valve by a direct pull upon the hose length required to be attached thereto. I am aware of previous efforts having the same purpose in mind; witness besides others, United States Letters Patent issued to Hunter No. 25 513,265; to Wirt No. 825,570 and to Featherstone No. 868,080.

As contradistinguished from these and such other constructions as have heretofore become known to the market, I have con- 30 trived:

(1) A structure that is readily attachable to a standard type of valve which has met with universal approval for the purpose.

(2) An arrangement by which the valve 35 is opened by direct lever action.

(3) A reinforcing of and mode of support for the attached hose length such that injury attendant upon its use is precluded.

An incidental object has been to provide 40 a contrivance which involves few parts, whose resetting or closing is readily comprehended, and which is simple, durable and economical of manufacture.

The inventive conception is associated 45 with means which are hereinafter explained and variously combined in the claims. While the annexed drawing and particular description thereof, jointly set forth in detail preferred and modified forms embody- 50 ing my invention, it should be understood that the means only exemplify some of many diversified mechanical forms with which the principle of my invention may be justly applied.

Adverting to the drawings:

Figure I is a side elevation of a standard type of valve (Lunkenheimer) showing my invention attached thereto in its closed position.

Fig. II is a view similar to Fig. I, showing the position of the elements of my invention when the valve is open.

Fig. III is a rear end view showing the position of the parts when the valve is closed.

Fig. IV is a broken view similar to Fig. III showing the position assumed by the parts when the valve is opened.

Fig. V is a section through the hose-length reinforced after the manner of my invention.

Fig. VI is a longitudinal section through one portion of the reinforcing medium.

Fig. VII is a side view of the modified form of my invention.

The valve which I have chosen for illustration in conjunction with my invention is of the standard lever-throttle or handy-gate type adapted for a quick opening. The construction of the valve will be seen to comprise an upper boss 1, a rear or inlet boss 2 of hexagonal contour, and a front or outlet boss 3 likewise of hexagonal contour. One side of the valve is furthermore provided with a projecting curvilinear boss 4 which is hollow for the purpose to be hereinafter mentioned. A connecting inlet pipe 5 is screw threaded in the boss 2 while an outlet connecting nipple 6 is similarly screw threaded in the boss 3. Inasmuch as nothing of an inventive character is claimed for the operative parts of the valve proper, only those few parts will be described which are visible and of general or direct interest for the purposes of this application. The gate 7 of the valve is shown in its open position in Fig. IV. A valve-stem 8 is operatively connected with the gate 7 in any feasible manner, and fixed to the stem 8 so as to be rotatable therewith is a valve-stem lever 9, which is the first part of my inventive conception to be described. The free extremity of this lever is provided with an opening 10. That surface of the lever 9 which is above is provided near the end other than the one in which the opening 10 is located, with an upwardly projecting boss 11, having a transversely projecting stop 12. The lever 9 is

furthermore formed intermediately of the opening 10 and the projection 11, with a small aperture 13. An auxiliary or hose actuated lever 14 is provided near one end 5 with an opening 15 adapted to register with the opening 10 and make possible a pivotal connection between the levers 9 and 14 through the medium of a pin 16. In this manner a compound action of the levers may 10 be had. The upper extremity 17 of the auxiliary lever 14 is of rounded contour to serve as a grip for the hand when it is desired to manipulate the valve. The auxiliary lever 14 is supplied at a corresponding distance 15 from the pin 16 with a small aperture 18 adapted to register with the aperture 13 when the valve is closed, for a purpose to be hereinafter made clear. The opposite or lower end of the auxiliary lever 14 is curved 20 toward the bottom of the valve and provided at its extremity with an opening 19. It should be apparent from an inspection of Figs. III and IV that any actuation of the auxiliary lever 14 must be transmitted to 25 the valve-stem lever 9, whereby the latter is swung around with it. The closing of the valve is most readily accomplished by pressing downwardly upon the grip 17, whereupon the upper surface of the auxiliary lever 30 14, with the pin 16 as a pivot, will presently engage the stop 12 and thereafter carry it and hence the lever 9 along with it about the valve stem 8 as a pivot. The purpose of the stop 12 is to insure an absolutely tight closure 35 of the valve when the grip 17 may have reached the limit of its downward travel.

According to the preferred form of my invention, I have provided a pair of brackets 20 and 21 respectively, which are adapted 40 to snugly embrace opposite sides of the valve body and support such other parts as are necessary to my invention. The bracket 20 which is best seen in Figs. 1 and 2, comprises a slightly curved upright provided 45 above with an arcuate transverse portion 22 adapted to conform to and abut the boss 1. The extremities of the arcuate portion 22 projects laterally to form ears 23, each provided with an opening 24. The lower extremity 50 of the bracket 20 is provided with a straight flat cross member 25, provided at opposite ends with openings 26. The bracket 20 is provided intermediate of its ends with an ear 27 which is also formed with an opening 28. The other bracket 21 is more sharply curved at 29 to conform with the exterior contour of the boss 4, as best shown 55 in Fig. III. The upper end of the bracket 21 is of corresponding formation as the upper end of the bracket 20 and includes an arcuate transversely disposed portion 30 having projecting extremities 31 which are similarly provided with openings 32. As 60 should now be apparent, the arcuate portion 22 and 30 form together a collar around the

boss 1. The lower end of the bracket 21 is also similarly formed as is the lower end of the bracket 20 to include a cross member 33 and a pair of openings 34 at opposite ends thereof. The two complementary collar 70 forming portions 22 and 30 are adapted to be drawn together through the agency of bolt and nut combinations designated entire with the reference character 35. The cross members 25 and 33 are adapted to secure and 75 support between them by means of suitable screws 36, a block 37. This block is preferably formed above with flat surfaces 38 adapted to lie contiguous to a pair of the hexagonal surfaces on the bosses 2 and 3 respectively, as clearly shown in Figs. I and II. The block 37 is moreover formed with a longitudinally extending bore 39, having widely flared end portions 40. It will be noted that the bore 39 extends in the direction 80 from front to rear with reference to the inlet and outlet of the valve. A member 41 provided with a hook 42 is swiveled to the bottom of the block 37 by means of a stud 43 passing therethrough. The hook 42 should 85 have only a slight incline and a smooth merging extremity as clearly shown in Figs. I and II.

A coupling 44 effects connection between the outlet pipe 6 and a hose-length 45 of any 90 approved construction. For a given distance from the coupling 44, I provide the hose 45 with a reinforcing shoe. The construction which will now be described will be best understood by alternate attention to 100 Fig. V. I prefer to have the construction of such shoe involve among other things a pair of flexible metal strips 46 running longitudinally on opposite sides of the hose. These strips are inclosed by a leather covering 47 105 and specifically in a fold or loop 48 formed at one end of each of a pair of complementary shoe forming members. Each of the folds or loops 48 supports on its outer side a metal projection 49. Each of the opposite 110 extremities of the two complementary portions of the shoe supports a concave snap 50, adapted to engage and lock with the projection 49 after the manner of the common glove snap. 115

The dimensions of the two complementary portions 47 should be such that when clasped together they will snugly embrace the fire hose which is to be used. At the extremity of the reinforcing shoe and along 120 the rear or under strip 46, I affix a metal supporting member 51 provided intermediate of its ends with a loop 52. This member may be secured to the strip 46 by means of rivets 53 as shown in Fig. VI. I have 125 also shown a pair of links 54 and 55 connecting with the loop 52. A chain 56 passes through the bore 39 to connect in the rear through the medium of its end link 57 with the opening 19 in the lower end of the aux- 130

iliary lever 14. The other end of the chain is provided with the conventional type of snap 58 which engages the link 55. In this manner, as will be readily understood, a 5 tugging upon the hose 45 will contrive to open the valve by pulling the levers 9 and 14 into the position best shown in Fig. IV. The link 54 which is directly connected to the loop 52 is preferably of rather large size 10 and adapted to rest loosely upon the hook 42 when the valve is closed as shown in Fig. I. In this manner the hose may be supported when not in use without injury to that portion thereof which is nearest the point of 15 support and also without injury and hence likelihood of leakage at its point of connection with the coupling 44. A wire 59 is adapted to pass through the opening 28 and through both openings 13 and 18 when the 20 latter register as they do when the valve is closed. The free ends of the wire 59 are then drawn together and secured with a leaden seal 60. Such sealing of fire valves of this character is to meet the requirements 25 of the municipal water works department to the end of precluding a waste of a free water supply for use other than in cases of fire quenching necessity. As will be apparent from an observance of Fig. IV, a 30 pulling upon the chain 56 will cause the auxiliary lever 14 to move relatively to the valve-stem lever 9 thereby first tending to sever the wire seal by a shearing action and finally positively disrupting the same.

35 The operation of my invention is exceedingly simple. After it has been attached to the valve, the latter is closed and the reinforcing shoe hung upon the hook as shown in Fig. I. Should a fire occur in the vicinity 40 of the particular standpipe with which my invention had been provided, a person is merely required to grasp the extremity or nozzle end of the hose 45 and hasten in the direction of the source of the heat. In the 45 meantime the swiveled hook would turn in the direction in which the hose was being carried and consequently when the same had been stretched to its full length would permit it to slide readily therefrom. There- 50 after a comparatively slight pull upon the hose by reason of its direct lever action assisted by the weight of the hose will contrive to open the valve and necessarily permit the flow of the water through the hose.

55 Before placing the hose upon a rack or in some suitable receptacle, it is expedient to dry the same. It is therefore desirable to be able to quickly detach the same and it is for this reason that the snap 58 has been 60 provided.

The modification disclosed by Fig. VII resides solely in making the block 61 integral with the bottom of the valve. Otherwise the construction and operation is identical including the shape and direction of

the extent of the bore 62 through which the chain 56 would in this instance be similarly drawn. The advantage, waiving the initial expense in altering the valve, consists in obviating the necessity for the brackets. 70

My invention being thus described with sufficient thoroughness, what I desire to secure by Letters Patent and therefore claim specifically, is:

1. In means for positively opening a valve 75 by pulling, the combination with a valve body, a hose coupled thereto, a hook swiveled upon said valve body, and a loop secured to a given portion of said hose and adapted to engage said hook.

2. In means for positively opening a valve by pulling, the combination with a standard valve body, a hose coupled thereto, a member removably clamped thereto, a hook 85 movably secured to said member, and a reinforcing strip carried by said hose, said strip having a loop adapted to engage said hook.

3. In means for positively opening a valve by pulling, the combination with a valve body, a hose coupled thereto, a depending 90 member removably attached thereto, a hook swiveled to said member, and a reinforcing device secured to said hose and including a loop spaced some distance from said coupling, said loop adapted to be supported 95 upon said hook.

4. In means for positively opening a valve by pulling, the combination of a pair of brackets adapted to embrace opposite sides of the valve body, means for drawing said 100 brackets together, a block carried by said brackets and provided with an opening, a hose coupled to said valve, a valve-stem lever, and a chain passing through said opening and connecting said hose and lever. 105

5. In means for positively opening a valve by pulling, the combination with a valve body, a valve-stem lever having an aperture, an auxiliary lever articulating with said valve-stem lever so as to have a shearing engagement therewith, said auxiliary lever having an aperture adapted to register with said aperture, and a seal including a portion passed through said apertures adapted to be severed by the co-action of said levers. 110

6. In means for positively opening a valve by pulling, the combination of a valve, and a compound lever for operating the same, and a seal connecting said lever components, said components adapted to have a shearing 120 action whereby to sever said seal.

7. In means for positively opening a valve by pulling, the combination of a valve, a valve-stem lever, a hose coupled to said valve, and an auxiliary lever connected with 125 said hose and with said valve-stem lever a wire seal limiting the relative movement of said levers, and with said valve stem lever adapted to sever such wire.

8. In means for positively opening a valve 130

by pulling, the combination of a valve body, a hose coupled thereto, a valve-stem lever, a hook carried by said valve body, another hood carried by said hose and adapted to engage said first mentioned hook, and a connection between said hose and lever.

9. In means for positively opening a valve by pulling, the combination of a valve-stem lever, a standard fire hose coupled to the valve, a quick detachable reinforcing shoe said shoe being flexible and adjustable along

said hose, and a limiting connection between said shoe and lever whereby the latter may be actuated in response to a pull upon the former.

15

Signed by me, this 23rd day of March, 1914.

HENRY WAIBEL.
